Application August 12, 1957, Serial No. 47,324

Term of patent 14 years

(Cl. D71—1)

Fig. 3

Fig. 1 is a side elevational view of a ship or similar article embodying my new design with a portion broken away to indicate an indeterminate length.

Fig. 2 is a fragmentary top plan view thereof as shown in Fig. 1.

Fig. 3 is a rear view thereof.

The side of the ship not shown is substantially the same in appearance as the side shown in Fig. 1.

I claim:

The ornamental design for a ship or similar article, as shown and described.
